Primary Examiner — George D. Kirschbaum*Assistant Examiner* — Suzanne E Tisdell(74) *Attorney, Agent, or Firm* — Faegre Drinker Biddle & Reath LLP(57) **CLAIM**

We claim the ornamental design for the vehicle seats, as shown and described.

DESCRIPTION

FIG. 1 is a left front perspective view of seats configured for a vehicle, and showing our new design of the seats, with the opposing right front perspective view as identical;

FIG. 2 is a left rear perspective view thereof, with the opposing right rear perspective view as identical;

FIG. 3 is a front view thereof;

FIG. 4 is a top view thereof; and,

FIG. 5 is a left side view thereof, with the opposing right side view as identical.

The portions of the vehicle seats shown in broken lines form no part of the claimed design.

1 Claim, 5 Drawing Sheets(56)
